UNITED STATES PATENT OFFICE.

GEORGE W. BAKER, OF CLEVELAND, OHIO, ASSIGNOR TO THE WHITE
SEWING MACHINE COMPANY, OF SAME PLACE.

SHUTTLE FOR SEWING-MACHINES.

SPECIFICATION forming part of Letters Patent No. 393,738, dated December 4, 1888.

Application filed September 12, 1887. Serial No. 249,442. (No model.)

To all whom it may concern:

Be it known that I, GEORGE W. BAKER, of Cleveland, in the county of Cuyahoga and State of Ohio, have invented certain new and 5 useful Improvements in Sewing-Machine Shuttles; and I do hereby declare the following to be a full, clear, and exact description of the invention, such as will enable others skilled in the art to which it pertains to make 10 and use the same.

My invention relates to improvements in sewing-machine shuttles; and it consists in certain features of construction and in combination of parts hereinafter described, and 15 pointed out in the claims.

In the accompanying drawings, Figure 1 is a plan view of the shuttle complete. Fig. 2 is a plan of the shuttle with the tension-spring removed. Fig. 3 is a plan of the tension-spring 20 detached. Fig. 4 is a rear end elevation.

A represents the body of the shuttle, consisting, in the main, of a hollow cylinder open-ended at the rear, and having a solid-pointed forward end, A', in which latter is set the spindle B. The spindle extends back through the center of the cylinder, and has mounted thereon the bobbin or thread-spool b. The shell of the shuttle has holes a and a' for attaching the spring C, and has a hole, a², for 25 the passage of the thread. A hole, a³, is made in the solid portion of the shuttle, and is countersunk for receiving the shank of the spring, the reduced bore of the hole being screw-threaded for receiving the screw d, that holds 30 the forward end of the spring, the desired tension being had by adjusting this screw. A thread-slot, A², commences at the heel or open end of the shuttle about midway up the side that lies against the shuttle-race, this slot running 35 diagonally forward and upward to hole a², the latter being located, as shown, near the top of the shuttle. A slight external thread-groove, A³, is made in the shell of the shuttle, leading from holes a² forward, as shown more 40 clearly in Fig. 2. A broader deeper groove, A⁴, commences about opposite holes a², but lower down the face side of the shuttle, and runs obliquely forward and upward to hole a³. A slight depression or pocket, a⁴, is located 45 substantially as shown in Fig. 2. The forward end or shank of spring C is offset down-

ward and terminates in an eye, C', that fits in the counterbore of hole a³, where it is secured by screw d. On the respective sides of the spring and integral therewith are slender bows C² and C³, the former having a lip, c², that covers hole a² and covers a portion of the thread-slot and groove adjacent to this hole. By means of this lip the thread as it passes from the bobbin up through hole a² is bent 60 down and held in and made to follow groove A³. Fingers c and c' are integral with the body of the spring and project, the one forward and the latter rearward, forming notches c³ and c⁴ between the respective fingers and 65 spring proper, these notches serving as ways for the thread to run in. The rear end of the body of the spring and of bow C³ are offset or made with hook ends for fastening, respectively, in the holes a and a'. (See Fig. 3.) 70 The outer edge of that portion of bow C² that extends over groove A⁴ is turned down or slightly depressed into this groove; also, the point of finger c' is depressed into pocket a⁴, leaving the upper surface of the finger end 75 about flush with the periphery of the shuttle.

In threading the shuttle, the bobbin having been placed on the spindle and the operator retaining the end of the thread in hand, the thread is entered in slot A² and drawn forward under bow C² until the thread enters hole a² and has passed under finger c, the thread thus being brought into groove A³ and into notch c³. From thence the thread is passed over the shank of the spring, and is 80 then drawn rearward under bow C³, and when the thread reaches the rear end of this bow it will have passed under finger c', entering notch c⁴. Next, by drawing the thread forward the thread is brought over the top of finger c', and leads from thence laterally under bow C³, from whence it passes to the work. To recapitulate, the thread, when in position, leads from the bobbin through hole a², thence along groove A³ to notch c³, thence over the 85 spring and back under the spring to notch c⁴, from thence over finger c', and out laterally under bow C³. The thread in its passage under the spring on its way to notch c⁴ is slightly compressed between the spring and 90 shuttle to give the desired tension, such tension being, as aforesaid, regulated by screw d.

I am aware that in cylindrical shuttles of the class aforesaid thread-slots have been used; but these were located in such position usually approximately on the opposite side of the shuttle from the thread-slot shown in the drawings, and consequently in such position that the slack thread was likely to catch in the end of such slot. With the construction shown, the outer end of the thread-slot being located opposite from where the thread leaves the shuttle and from where the slack thread depends, there is nothing to cause the slack thread to catch in slot A², and, besides, there is not length enough of the slack thread to reach this slot, and consequently the objectionable feature heretofore met with thread-slots for the purpose is entirely overcome.

What I claim is—

1. A cylindrical shuttle having a thread-slot commencing at the rear or open end of the shuttle, midway up the face side thereof,

and running from thence diagonally forward and upward to near the top of the shuttle, substantially as set forth.

2. The combination, with cylindrical shuttle having a thread-slot commencing at the heel of the shuttle, on the face side thereof, and running diagonally forward and upward, of tension-spring mounted on the shuttle, said spring having fingers c and c', located substantially as shown, whereby the thread in passing from one side of the spring to the other side is made to pass over and around the spring, substantially as set forth.

In testimony whereof I sign this specification, in the presence of two witnesses, this 3d day of September, 1887.

GEORGE W. BAKER.

Witnesses:

CHAS. H. DORER,

ALBERT E. LYNCH.
